2 Claims. (Cl. 200—87)

The disconnecting switches of electric lines are generally formed with a knife blade forming a loop with the current leads. When a short circuit occurs a field is generated within the loop and the forces thus generated open the disconnecting switch.

5 A disconnecting switch of this character cannot be utilized on lines where short circuit currents are heavy in view of the fact that the knife blade would open at each short circuit.

The present invention avoids this disadvantage. It has for its object a disconnecting switch characterized in this that the current leads form at least at one of the ends of the knife blade a 10 loop which gives to the electrodynamic forces acting on the knife blade a direction such that the opening of the knife under the action of short circuit currents may be avoided.

Figs. 1 and 2 show respectively a schematic arrangement and a part view of a disconnecting switch in accordance with the invention and Figure 3 is a diagrammatic representation of a modified form of the invention whereof one side loop is dispensed with. The knife blade is denoted by 15 C and the two loops formed by the conductors by a, b, c, d, and by a', b', c', d'. The disconnecting switch opens by moving the knife blade upwards. The apparatus thus forms three loops, a large loop D d', E, as also two small loops a b c d and 20 a' b' c' d'. These three loops generate electrodynamic forces F₁, F₂, F₃, the first of which is directed upwards while the two others tend to oppose the opening of the knife blade. The dimensions a d, d d' and d' a' are so selected that the 25 resultant of the three forces F is directed downwards and consequently opposes the opening of the knife blade.

By suitably selecting the dimensions of the loop a, b, c, d, the loop a' b' c' d' may be dispensed with and nevertheless a resultant F directed downwards obtained. This is shown in Fig. 3, wherein the blade is pivoted at A and opens the line 60 at X.

In the construction illustrated in Fig. 2 the current is lead in by way of a terminal P from which extend two shaped conductors G at the free end of which is fixed a contact having jaws M. The 65 parts G thus form the loop designated by a b c d in Fig. 1. One of the arms G may be dispensed with.

Having now particularly described and ascertained the nature of my said invention and in 70 what manner the same is to be performed, I declare that what I claim is:

1. A disconnecting switch for electric lines, comprising a movable knife blade adapted to connect the two extremities of a part of an electric 75 line, knife blade supports carrying the line current and forming with the blade a first loop, the blade moving away from the center of this loop to open the line, and a loop formed by one extremity of the blade support with the corresponding 80 end of the blade, and above said blade, the second loop being opposed to the first.

2. In a disconnecting switch, a displaceable knife blade forming several loops with the extremities of an electric line which said blade connects together, and a forked support at the opening end of the blade and constituted by the extremities of the line to be opened, said forked support constituting a loop above the blade and 85 in planes parallel to the plane of said blade and 90 at each side thereof.

CHARLES BRESSON.
